COMBINED PIPE CLEANER AND ASH RECEIVER

Martin A. Mikesh, Lawrenceville, N. J.

Application May 2, 1933, Serial No. 668,960

12 Claims. (Cl. 131—51)

This invention relates to a combined pipe cleaner and ash receiver.

It is well known to pipe smokers that after every smoke periodically the inside of a smoking pipe bowl must be scraped to free the ash and other material that adheres to the inner surface of the bowl and the pipe must be thereafter tapped in an inverted position to cause the thus freed material to fall from the pipe bowl.

16 The principal argument of the present invention is to provide a device, by means of which the ash and other material may be freed from the inner surface of the smoking pipe bowl, and may be dislodged from the bowl after being thus freed, and automatically conveyed to an ash receptacle.

In the drawing I have illustrated one form of the invention but it is, of course, to be understood that the invention may take various other forms within the definition of the claims.

20 Figure 1 is a top plan view of an embodiment of the invention;

Figure 2 is a side elevation thereof, and

Figure 3 is a front view.

The form illustrated includes a base member 1 that is provided with a depression in which an ash receptacle 2 is removably mounted.

This base 1 may be provided with depressions 3, for the reception of pipes, to maintain them in the position illustrated in dotted lines in Figure 2.

30 Extending upwardly from the base 1 is a standard 4 which is, at its upper end, provided with a curved surface 5 that inclines downwardly toward the ash receptacle 2.

The raceway 6 is mounted upon the upper curved surface 5 of the standard 4, and likewise inclines downwardly toward and overlaps the receptacle 2. The sides of this raceway 6 are relatively higher than the medial line of the raceway from the top to bottom thereof, in the form illustrated in the drawing the raceway is curved laterally, which produces this effect.

This raceway 6 is preferably made of a material softer than the material of the pipe, so as to lessen the damaging effect on the pipe when 45 tapping the same on the raceway, and yet of sufficient rigidity to maintain its form.

Extending upwardly from the raceway 6 and located between the side and top and bottom edges is a pipe cleaner 8. In the form shown this cleaner is rectangular in horizontal cross-section at the portion which is insertable into the pipe bowl. The longitudinal edges 9 of this pipe cleaner 8 are sharp and the upper end is formed into a knife blade that is curved, as at 10.

55 In the embodiment of the invention disclosed

in the drawing, the pipe cleaner 8 extends completely through the raceway 6 and the standard 4 to the base 1, to which it may be attached in any suitable manner, but it is obvious that the pipe cleaner may be attached in any other desirable manner, the essential requirement being that it extend upwardly from the raceway 6.

In using this device, the smoking pipe is inserted and the pipe cleaner 8 inserted within the bowl. The pipe may then be partly or completely revolved, and the longitudinal edges 9 will free the sides of the inner surface of the bowl of ashes and other material that adheres thereto, while the upper curved edge 10 will free the bottom of the bowl of such material, the curvature being for the purpose of conforming to the configuration of the bottom of the bowl.

The pipe bowl being thus freed of the foreign material, the pipe may then be removed from the cleaner 8 and tapped upon the upper surface of the sides of the raceway 6. Thus tapped, the freed material will fall from the bowl to the raceway 6, and by the raceway be conveyed to the receptacle 2.

What I claim is:

1. In a device of the class described, a base, an ash receptacle on said base, a smoking pipe cleaner extending upwardly from the base and independent of the receptacle, and a raceway to convey material from said cleaner to said receptacle.

2. In a device of the class described, a base, an ash receptacle on said base, a smoking pipe cleaner extending upwardly from the base and independent of the receptacle, and a leather raceway to convey material from said cleaner to said receptacle.

3. In a device of the class described, a base, an ash receptacle on said base, a smoking pipe cleaner extending upwardly from the base and independent of the receptacle, and a raceway to convey material from said cleaner to said receptacle, said raceway being laterally curved and longitudinally inclined toward the receptacle.

4. In a device of the class described, an ash receptacle, a raceway extending thereto, and a pipe cleaning device protruding above the raceway between its top and bottom and side edges and independent of the receptacle.

5. In a device of the class described, an ash receptacle, a raceway extending thereto, and a pipe cleaning device protruding above the raceway between its top and bottom and side edges, the sides of said raceway being higher than the central portion thereof.

6. In a device of the class described, a base, a standard extending upwardly from said base, a raceway supported by said standard and a pipe cleaner extending upwardly from the raceway, 5 the width of said raceway being greater than the width of the surface of the standard with which the raceway contacts.
7. In a device of the class described, a base, an ash receptacle on said base, a smoking pipe cleaner extending upwardly from the base, and 10 an element disposed above and adjacent an edge of the base and adapted to serve as a base for tapping the pipe and so formed as to comprise a raceway for conveying the material discharged 15 from the pipe to said ash receptacle.
8. In a device of the class described, a base, an ash receptacle on said base, a smoking pipe cleaner extending upwardly from the base, and 20 a leather element disposed above and adjacent an edge of the base and adapted to serve as a base for tapping the pipe and so formed as to comprise a raceway for conveying the material discharged 25 from said pipe to said ash receptacle.
9. In a device of the class described, an ash 30 receptacle, an element disposed above and adjacent an edge of the receptacle and adapted to serve as a base for tapping the pipe and so formed
- as to comprise a raceway for conveying the material discharged from said pipe to said ash receptacle, and a pipe cleaning device protruding above the raceway between its top and bottom and side edges, the sides of said raceway being elevated with respect to the central portion thereof.
10. In a device of the class described, a base having an ash receptacle, a pipe cleaning element extending upwardly from the base and without the outer edge of the receptacle and a raceway extending from the pipe cleaning device to the receptacle.
11. In a device of the class described, a base having an ash receptacle, a pipe cleaning element extending upwardly from the base and without the outer edge of the receptacle and a raceway extending from the pipe cleaning device to the receptacle, the sides of said raceway being higher than the central portion thereof.
12. In a device of the class described, an ash receptacle, an inclined raceway extending there- 40 to, and a pipe cleaning device protruding above the raceway between its top and bottom and side edges.
